CLOTH LAYING UP MACHINE

Joseph M. Perignat, Forest Hills, N. Y., assignor
to Consolidated Sewing Machine & Supply Co.,
Inc., New York, N. Y., a corporation of New
York

Application November 18, 1948, Serial No. 60,761

4 Claims. (Cl. 270—31)

1

This invention relates to cloth laying up machines and more particularly to an improved drive mechanism for the fold forming member of such machines.

As is well known, such machines include a carriage which is mounted to reciprocate on a table and which carries a frame in which the fold forming member is mounted. This fold forming member is vertically slidably mounted in the frame and is adapted to be rotated through an arc of 180° on each reciprocation of the table to form the end folds in the layers of cloth.

The present invention is directed to a simplified means for effecting this movement of the fold forming member. The fold forming member is mounted on a horizontal stub shaft and this shaft is connected by gearing to a vertical shaft having a segmental gear on its lower end. The segmental gear meshes with a rack carried by a bar secured to the carriage. On the vertical shaft and adjacent the gear I provide a disc having a semi-circular edge portion and adjacent flattened portions. A bar having a recess extending throughout the length of the rack and having adjacent portions adapted to be engaged by the flattened portions of the disc is associated with the rack.

Thus, instead of the complicated mechanical movements heretofore provided for turning the fold forming member exactly 180° and then stopping its movement, I accomplish this purpose by a simple rack and pinion construction with means associated with the rack and pinion to arrest the movement of the shaft at the end of 180°.

In the accompanying drawing I have shown a portion of a cloth laying up machine showing the invention applied. In this showing:

Fig. 1 is a side elevation of a portion of the table and the carriage with which the frame and fold forming member are associated;

Fig. 2 is a vertical, sectional view on line 2—2 of Fig. 1;

Fig. 3 is a horizontal, sectional view on line 3—3 of Fig. 1 showing the drive at one end of its movement;

Fig. 4 is a similar view showing the drive at the other end of its movement; and

Fig. 5 is a detailed view, schematically showing layers of the cloth as folded by the fold forming member.

Referring to the drawing, the reference numeral 1 designates a table on which a carriage 2 is reciprocated in any suitable manner. The end of the carriage carries a frame 3 having a slot 4 therein to receive a block 5 which carries the

2

fold forming member 6 and which reciprocates in the slot 4 to raise and lower the fold forming member as folds F of the cloth C are piled on the table (see Fig. 5). The block 5 and the fold forming member are raised and lowered in the frame by suitable mechanism generally designated at 7 but not specifically described herein as such mechanism forms no part of the invention. As shown, the fold forming member is 10 channel shaped comprising a back 8 and arms 9. The back is provided with a slot and a plurality of rolls 10 are arranged adjacent this slot to guide the cloth through the fold forming member in the usual manner.

15 A stub shaft 11 is secured to the fold forming member and extends through the block 5. This stub shaft carries a bevel gear 12 meshing with a bevel gear 13 on a vertical shaft 14. To permit the fold forming member to move up and down and keep the gears 12 and 13 in mesh at all times, the gear 13 is movable longitudinally of the shaft 14 but is keyed to the shaft to revolve therewith. As shown, the upper end of shaft 14 is mounted in a bearing formed in a bracket 15 secured to the frame and the lower end is received in a bearing box 16. Block 5 carries an arm or plate 17 having an opening through which shaft 14 extends, the shaft being free to revolve in this opening. Plate 17 in turn carries a hub member 18 which is longitudinally movable with the plate but free to revolve with respect thereto. The hub 18 is connected to gear 13 to revolve therewith. Shaft 14 is provided with a key-way 19 to receive a key 20 carried by the hub 18.

25 On the lower end of the shaft 14 I provide a segmental gear 21. As shown (see Figs. 3 and 4) the teeth 22 of this gear extend through slightly more than 180°. These teeth mesh with the teeth of rack 23, which rack is carried by a bar 27 slidably mounted in the bearing box 16. The number of teeth in rack 23 are just sufficient to turn gear 21, and therefore the shaft 14, through an arc of 180°.

Associated with the gear 21 I provide a disc 24 having two curved sections 25 slightly less than 180° connected by two flattened sections 26. The edge of bar 27 is substantially in the vertical plane with the crests of the teeth 23, but it is provided with a recess 28 which extends inwardly to a point beyond the root of the teeth of the rack 23.

In operation, as the carriage 2 reciprocates, rack 23, bar 27 and gear 21 reciprocate with the carriage without relative motion throughout the greater portion of the stroke of the carriage.

Just before the end of the stroke, bar 27 engages a stop 29 (see Fig. 1). One of these stops is mounted at each end of the table 1 to be engaged by the bar 27. As the bar is brought to a state of rest, the carriage continues to the end of its stroke and this relative movement between the two causes teeth 22 and 23 to mesh imparting a rotary movement to the shaft 14. Gears 12 and 13 are in mesh at all times, the hub 18 and associated parts moving up and down on the shaft 14 as the fold forming member moves up and down in the frame. Gears 12 and 13 are of the same size so that upon a 180° rotation of shaft 14, stub shaft 11 and the fold forming member will be oscillated through the same arc. The fold forming member 6 is spaced sufficiently above the top layer of the cloth to permit oscillation thereof.

The number of teeth in the rack are just sufficient to rotate the gear 180°. While the rack is in engagement with the teeth of the gear and rotating the gear in one direction, the curved portion 25 of the edge of disc 24 is in alignment with the adjacent portion of the bar 27 and rides in recess 28. As the end of the stroke is reached, one of the flattened portions 26 of the disc engages the edge of bar 27 beyond the end of the recess 28 and thus limits the movement to exactly 180°. The fold forming member is thus reversed at the end of each movement of the carriage and the horizontal arms form the folds in the cloth in the usual manner.

I claim:

1. A cloth laying up machine comprising a table, a carriage reciprocating on the table, a frame mounted on the carriage, a fold forming member pivotally mounted in the frame, a stub shaft secured to the fold forming member, a rack bar slidably mounted on the carriage, a shaft mounted on the frame a segmental gear secured to the shaft and meshing with the teeth of the rack, means carried by the shaft and engaging the rack bar to limit the movement of the shaft to 180°, an operating connection between the shaft and the stub shaft, and a stop in the path of the rack bar to bring it to a state of rest prior to the end of the stroke of the carriage to cause the rack bar to rotate the shaft and thereby operate the fold forming member.

2. A cloth laying up machine comprising a table, a carriage reciprocating on the table, a frame mounted on the carriage, a fold forming member pivotally mounted in the frame, a stub shaft secured to the fold forming member, a rack bar slidably mounted on the carriage, a shaft mounted on the frame, a segmental gear

secured to the shaft and meshing with the teeth of the rack, the number of teeth on the rack being sufficient to rotate the segmental gear and shaft through an arc of 180°, means for arresting the motion of the shaft when it has traveled 180°, operating connections between the shaft and the stub shaft, and a stop in the path of the rack bar to bring it to a state of rest prior to the end of the stroke of the carriage.

3. A cloth laying up machine comprising a table, a carriage reciprocating on the table, a frame mounted on the carriage, a fold forming member pivotally mounted in the frame, a stub shaft secured to the fold forming member, a rack bar slidably mounted on the carriage, a shaft mounted on the frame, a segmental gear secured to the shaft and meshing with the teeth of the rack, a disc carried by the shaft and cooperating with the rack bar beyond the rack teeth to limit the rotation of the shaft to an arc of 180°, operating connections between the shaft and the stub shaft, and a stop in the path of the rack bar to bring it to a state of rest prior to the end of the stroke of the carriage.

4. A cloth laying up machine comprising a table, a carriage reciprocating on the table, a frame mounted on the carriage, a fold forming member pivotally mounted in the frame, a stub shaft secured to the fold forming member, a rack bar slidably mounted on the carriage, a shaft mounted on the frame, a segmental gear secured to the shaft and meshing with the teeth of the rack, a disc carried by the shaft, the disc being of substantially the same diameter as the segmental gear and being provided with flattened portions at spaced intervals, the flattened portions of the disc being adapted to engage the side of the rack bar beyond the rack teeth to arrest rotation of the shaft, operating connections between the shaft and the stub shaft, and a stop in the path of the rack bar to bring it to a state of rest prior to the end of the stroke of the carriage.

JOSEPH M. PERIGNAT.
